See application file for complete search history.

FIG. 1 is a top perspective view showing the mounting platform for a mobile telephone of the present invention; FIG. 2 is a bottom perspective view thereof;

FIG. 3 is a top plan view thereof;
FIG. 4 is a right side view thereof;
FIG. 5 is a left side view thereof;
FIG. 6 is bottom plan view thereof;
FIG. 7 is a front view thereof; and,
FIG. 8 is a rear view thereof.

The broken lines in the drawing depict environmental subject matter only and form no part of the claimed design.
